SNOWSHOE GUIDE AND CLIMBER

William R. Walsh, Jarbidge, Nev.

Application November 15, 1954, Serial No. 468,808

4 Claims. (Cl. 36—4.5)

The present invention relates to new and useful improvements in shoe clamps for snowshoes and has for its primary object to provide a snowshoe attachment which will solidly anchor the snowshoe and prevent slipping and sliding while walking, as well as to provide a guide for the snowshoe which will prevent the usual hazard of misalignment between the shoe and the snowshoe.

An important object of the invention is to provide an easily attachable and replaceable clamp embodying a novel hinge structure for the clamp to permit inward and outward adjustment of the sides of the clamp to fit shoes of various sizes and at the same time permitting free bending of the foot while walking.

Another object is to provide an attaching plate at the underside of the snowshoe for the clamp and having portions which project downwardly below the snowshoe to form ice cleats.

A further object is to provide a device of this character of simple and practical construction, which is efficient and reliable in operation, relatively inexpensive to manufacture and otherwise well adapted for the purpose for which the same is intended.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a top plan view;

Figure 2 is an enlarged perspective view of the clamp;

Figure 3 is an enlarged fragmentary longitudinal sectional view taken on a line 3—3 of Figure 1;

Figure 4 is an enlarged fragmentary top plan view;

Figure 5 is an enlarged fragmentary top plan view showing the shoe clamping plates folded forwardly, and

Figures 6 and 7 are transverse sectional views taken respectively on the lines 6—6 and 7—7 of Figure 4.

Referring now to the drawings in detail, wherein for the purpose of illustration I have disclosed a preferred embodiment of my invention, the numeral 5 designates the clamp generally and which comprises a pair of upper hinge plates 6 and 7 positioned in side by side relation to each other and formed with aligned hinge pin eyes 8 and 9 at one end to receive a hinge pin 10. A lower hinge plate 11 is positioned in underlying bridging relation with respect to the pair of upper hinge plates 6 and 7 and plate 11 is also formed with aligned hinge pin eyes 12 for also receiving the hinge pin 10. The hinge pin is removable to permit placing the hinge eyes of the plates 6 and 7 inwardly or outwardly in their alternate arrangement with respect to the eyes of plate 11 to adjust the plates 6 and 7 inwardly or outwardly to fit shoes of different widths.

The clamp is attached on top of a snowshoe 13 by means of an attaching plate 14 positioned under the snowshoe and having bolts 15 passing through the lower

2

plate 11, web 16 of the snowshoe and attaching plate 14 and with the nuts 17 at the lower ends of the bolts forming cleats for use on ice. The free ends of upper plates 6 and 7 extend longitudinally rearwardly of their hinged front ends and front and rear flanges 18 and 19 extend upwardly at the outer side edges of the upper plates to receive the sole of a shoe 20 therebetween. Leather toe clamping members 21 and 22 are riveted to the front flanges 18 to overlie the toe of the shoe and are secured 10 on top of the shoe by lacing 23. An adjustable leather strap 24 is attached to the rear flanges 19 to extend over the instep portion of the shoe.

An adjustable heel strap 25 is also attached to the front flanges 18 and 19 and extends rearwardly therefrom at each side of the shoe and behind the heel thereof.

An adjusting plate 26 is positioned in bridging relation on top of the rear end portions of the pair of upper hinge plates 6 and 7 and is formed with a row of openings 27 to selectively receive bolts and nuts 28 carried by the upper hinge plates to secure the rear ends of the latter in inwardly or outwardly adjusted position.

The attaching plate 14 is formed at its outer ends with downwardly extending cleats 29 to aid in walking or 25 climbing on hillsides.

The clamp is secured in position on the snowshoe by attaching the lower hinge plate 11 on top thereof by the bolts and nuts 15 which pass through the web of the snowshoe to the attaching plate 14 at the underside of the snowshoe. After the hinge plates 6 and 7 have been 30 adjusted inwardly or outwardly to fit the size of the shoe the latter is clamped to the plates between the flanges 18 and 19 by the toe straps 21 and 22 and the instep and heel straps 24 and 25. The hinge connection for plates 6 and 7 will enable the person to bend his foot in the customary manner while walking.

From the foregoing, the construction and operation of the device will be readily understood and further explanation is believed to be unnecessary. However, since 40 numerous modifications and changes will readily occur to those skilled in the art, it is not desired to limit the invention to the exact construction shown and described, and accordingly, all suitable modifications and equivalents may be resorted to, falling within the scope of the 45 appended claims.

What is claimed as now is as follows:

1. A shoe clamp attachment for snowshoes comprising 50 a lower clamping plate, a hinge structure including a lower hinge plate and a pair of upper hinge plates hingedly connected to the lower hinge plate, means securing the upper hinge plates in an inwardly or outwardly adjusted position relative to each other, means attaching the first and second named plates in clamping engagement respectively under and on top of the snowshoe, and shoe clamping means carried by said pair of upper hinge plates.

2. A shoe clamp attachment for snowshoes comprising 55 a lower clamping plate, a hinge structure including a lower hinge plate and a pair of side by side upper hinge plates hingedly connected to the lower hinge plate, means securing said pair of hinge plates in inwardly and outwardly adjusted position relative to each other, means attaching the first and second named plates in clamping engagement respectively under and on top of the snowshoe, and shoe clamping means carried by said pair of upper hinge plates.

3. A shoe clamp attachment for snowshoes comprising 60 a lower clamping plate, a hinge structure including a lower hinge plate and a pair of side by side upper hinge plates hingedly connected to the lower hinge plate, means securing said pair of hinge plates in inwardly and outwardly adjusted position relative to each other, means

attaching the first and second named plates in clamping engagement respectively under and on top of the snowshoe, and front and rear shoe clamping straps attached to said pair of upper hinge plates.

4. A shoe clamp attachment for snowshoes comprising a lower clamping plate, a hinge structure including a lower hinge plate and a pair of side by side upper hinge plates hingedly connected to the lower hinge plate, means securing said pair of hinge plates in inwardly and outwardly adjusted position relative to each other, means 10 attaching the first and second named plates in clamping

engagement respectively under and on top of the snowshoe, and toe and heel shoe clamping straps attached to said pair of upper hinge plates.
